US00D837198S

(12) **United States Design Patent** (10) **Patent No.:** **US D837,198 S**
Entwistle (45) **Date of Patent:** **** Jan. 1, 2019**

(54) **FRAME MEMBER FOR A MOUNTING UNIT FOR AUDIOVISUAL DEVICES**

(71) Applicant: **URBEN TECHNOLOGIES LIMITED**, St Albans, Hertfordshire (GB)

(72) Inventor: **Mike Entwistle**, St Albans (GB)

(73) Assignee: **Urban Technologies Limited**, St Albans, Hertfordshire (GB)

(**) Term: **15 Years**

(21) Appl. No.: **29/583,428**

(22) Filed: **Nov. 4, 2016**

(30) **Foreign Application Priority Data**

May 5, 2016 (EM) 003111756-0001

(51) **LOC (11) Cl.** **14-03**

(52) **U.S. Cl.**

USPC **D14/251**; D16/200

(57) **CLAIM**

The ornamental design for a frame member for a mounting unit for audiovisual devices, as shown and described.

DESCRIPTION

FIG. 1 is an upper perspective view of the frame member for a mounting unit for audiovisual devices showing my design. FIG. 2 is an end elevation view thereof, an opposite end elevation view being a mirror image thereof;

FIG. 3 is a top plan view thereof;

FIG. 4 is a bottom plan view thereof;

FIG. 5 is a side elevation view thereof, an opposite side elevation view being identical; and,

FIG. 6 is a perspective view thereof, showing the frame member in a mounting unit in broken lines.

The line break symbols in FIGS. 1 and 3-5 indicate the appearance of any portion of the article between the line breaks forms no part of the claimed design.

1 Claim, 3 Drawing Sheets
